FREQUENCY DIVISION CIRCUIT

Westley F. Curtis, Washington, D. C.

Application November 5, 1932, Serial No. 641,445

15 Claims. (Cl. 250—36)

(Granted under the act of March 3, 1883, as
amended April 30, 1928; 370 O. G. 757)

My invention relates broadly to frequency division systems and more particularly to a polyphase frequency division system.

One of the objects of my invention is to provide a system of circuits for effecting a division in frequency of an impressed frequency simultaneously with the multiplication of phase of the impressed frequency.

Another object of my invention is to provide a relaxation circuit oscillator system having circuits connected in polyphase arrangement and adapted to generate polyphase oscillations under control of single phase impressed energy for effecting a division in frequency of the impressed energy.

Still another object of my invention is to provide a relaxation circuit oscillator system employing triodes connected in polyphase arrangement and having means for controlling the circuit connected with the control grids of the triodes from a single phase source whose frequency is to be divided for deriving a polyphase current at a submultiple frequency of the impressed frequency.

A further object of my invention is to provide a relaxation circuit oscillator system employing tetrodes connected in polyphase arrangement and having means for controlling the circuit connected with the screen grids of the tetrodes from a single phase source which is to be divided in frequency and a submultiple of the impressed frequency obtained.

A still further object of my invention is to provide a relaxation circuit oscillator system employing tetrodes connected in polyphase manner with means for controlling the circuit connected with the control grids of the tetrodes for effecting a division in frequency of the impressed frequency.

Other and further objects of my invention reside in the arrangement of a frequency division circuit as more fully set forth in the specification hereinafter following by reference to the accompanying drawings, in which:

Figure 1 shows the circuit of my invention embodying a triode tube, with the plate electrodes connected in delta and having impedance coupling between the output circuit of one tube and the input circuit of an adjacent tube, the control energy being applied to the control grid; Fig. 2 shows a modified form of the triode frequency divider of Fig. 1, wherein the grid electrodes are connected in delta and the input and output circuits of adjacent tubes intercoupled through impedance coupling, the control currents being impressed upon the control grid for effecting

the frequency division; Fig. 3 illustrates a Y-connected system wherein the plates are disposed in Y, and the grid electrodes are connected in Y, with the output and input circuits of adjacent tubes coupled through an impedance coupling system, and the subharmonic frequency of polyphase characteristics derived in the output circuit upon the impression of the high frequency energy upon the input circuit; Fig. 4 shows the circuit of my invention wherein the triodes have their plates connected in delta and the input and output circuits of adjacent tubes coupled through resistance elements and arranged for the operation of the system as a frequency divider; Fig. 5 shows another form of my invention wherein the grid electrodes are disposed in delta and the input and output circuits of adjacent tubes intercoupled through resistance elements, the control currents being applied to the grid for deriving the sub-harmonic polyphase current in the output system; Fig. 6 shows a Y connected system embodying my invention wherein the plate electrodes are disposed in Y and the grid electrodes connected in Y, with the input and output circuits of the adjacent tubes coupled through resistances; Fig. 7 shows an arrangement of my invention in which the electron tubes have their circuits connected in delta with the input and output circuits of adjacent tubes inductively coupled, the circuits being arranged to receive high frequency energy and deliver a subharmonic polyphase current; the grid electrodes are connected in delta; Fig. 8 shows the triodes with their plate circuits arranged in delta, and the input and output circuits of adjacent tubes inductively coupled for establishing the oscillatory system which receives the high frequency energy and derives the sub-harmonic energy at polyphase characteristics.

Fig. 9 shows a Y connected system in which the plate electrodes are connected in Y and the grid electrodes connected in Y, with the input and output circuits of adjacent tubes inductively coupled and the circuits arranged for the impression of high frequency energy on the control grid for deriving polyphase sub-harmonic energy in the output circuit of the several tubes; Fig. 10 shows an arrangement embodying the invention in which screen grid tubes are connected in a Y connected system, the grids being in Y, the plate electrodes being connected in Y, and the screen grid electrodes being connected in Y with the control on the screen grid and the output circuit of one electron tube inductively coupled to the input circuit of a succeeding electron tube.

in the oscillator system; Fig. 11 shows a delta connected system having the input and output circuits of the tubes transformer coupled one to the other, with control on the screen grid for receiving a relatively high frequency and deriving a lower sub-harmonic frequency of three phase characteristic, the control grids are delta connected; Fig. 12 shows a further modified form of the circuit of the invention in which the screen grid tubes are connected with their plates disposed in delta arrangement, the input and output circuits of the tubes being inductively coupled; Fig. 13 shows a further modified form of the circuit of the invention employing screen grid tubes, 15 with the plate electrodes arranged in delta, with control on the screen grid and having impedance coupling between the electron tubes; Fig. 14 shows another modified form of the circuit of the invention wherein the screen grid tubes are arranged with their circuits disposed in Y, that is, the plate circuits are connected in Y, the screen grid circuits upon which the control is impressed are arranged in Y, and the control grids are disposed in Y, the control current being impressed 20 upon the screen grid for deriving the lower frequency polyphase current in the output circuit, the output circuit of one electron tube being impedance coupled with the input circuit of the succeeding tube; Fig. 15 shows a further modified 25 form of the circuit of my arrangement, the grid electrodes being arranged in delta and the input and output circuits of the adjacent tube being impedance coupled, the control current being applied to the screen grid of each of the tubes for 30 deriving the sub-harmonic frequency from the impressed high frequency energy; Fig. 16 shows another modified form of circuit embodying the invention in which the screen grid tubes are arranged with their plate circuit connected in delta 35 and the circuits of one tube coupled to the circuits of an adjacent tube through a resistance coupling, the control being applied to the screen grid in each instance for deriving the sub-harmonic frequency from the impressed high 40 frequency energy; Fig. 17 shows another form of the invention in which the grid circuits are connected in delta and the adjacent tube interconnected through resistance coupling with control potential applied to the screen grid; Fig. 18 shows 45 a Y connected system wherein the screen grid tubes have their grids connected in Y, their plate electrodes connected in Y and the screen grids connected in Y, with the circuit of one screen grid tube interconnected with the circuit of an adjacent screen grid tube through resistance 50 coupling and control potential applied to the screen grid of each of the tubes for deriving the sub-harmonic frequency of polyphase characteristic; Fig. 19 shows a circuit arrangement embodying the principles of my invention in which 55 the electron tubes have the plate circuit delta connected and the tube circuits are inductively coupled, the control of the several circuits being on the control grid; Fig. 20 illustrates a modified arrangement of the electron tube circuit wherein the electrodes of the tubes are connected in Y with impedance coupling between the several circuits of the electron tubes, with the control being 60 upon the control grid of each tube; Fig. 21 shows a further modified form of the circuit of the invention in which resistance coupling is employed for interconnecting the several circuits of the tubes, the control being upon the control grid and the system being wholly Y connected; Fig. 22 shows a further modified form of the circuit of 65

the invention wherein the control is upon the control grid and in which control is effected upon the control grid and the circuits of the several tubes are impedance coupled, the screen electrode being connected in delta for establishing the oscillatory circuit for the conversion of the impressed high frequency energy into three phase energy of lower frequency; Fig. 23 shows an arrangement of the electron tubes in the frequency division system of the invention wherein the control is applied to the control grid, and the screen grids of each of the tubes are connected in delta utilizing resistance coupling; Fig. 24 shows a further modified form of the circuit of the invention wherein the screen grids of each of the tubes are connected in delta and the circuits of the several tubes inductively coupled for establishing the oscillatory path through the frequency division system, the control for the several tubes being applied to the control grid; Fig. 25 shows a further modified form of the invention wherein a Y connected system for the grid circuit and the plate circuit of the several tubes is provided with the control applied to the control grid, the screen grids also being connected in Y; Fig. 26 shows another form of the circuit of the invention wherein the plate electrodes are connected in delta for the several tubes with resistance coupling between the input and output circuits of each of the several tubes and control applied to the control grid; and Fig. 27 shows another form of my invention with control applied to the control grids of the several tubes and the input and output circuits of the tubes connected through impedance coupling means, with the plate electrodes connected in delta, the tube circuits being impedance coupled between the tubes; that is, between adjacent tubes, and not coupled between the input and output circuits of the same tube. 30

Summarizing the drawings, it will be observed that Figs. 1-9 show the frequency division system of my invention in which a high frequency is impressed upon the input system and a three phase current of a sub-harmonic frequency is obtained from the output side; Figs. 10-18 show the frequency division system of my invention using tetrodes with the control on the screen grids; and Figs. 19-27 show the frequency division system of my invention employing tetrodes connected in polyphase arrangement with the control on the control grids whereby a single phase high frequency current is impressed upon the three phase electron tube circuit and a three phase low frequency current derived therefrom. 45

I have discovered that any electron tube amplifier, whether resistance, inductance, or transformer coupled, can be made to function as a relaxation oscillator by properly coupling the output to the input, and that in general the number of phases produced by the oscillator can be made equal to the number of stages in the amplifier. Further, certain single-phase relaxation oscillators which do not readily fall in the amplifier class can be adapted to multi-phase operation. 50

Such an oscillator has many applications. 65 First, it is capable of producing multiphase current of frequency f from single phase current of frequency nf , where n is an integer. This multiphase current may be utilized for driving a synchronous motor clock, for measuring the higher 70 impressed frequency, or for controlling a synchronous motor from a piezo electric or magnetostrictive oscillator for any purpose where extreme constancy of speed and a high degree of precision is required. Second, the system of my invention 75

is capable of producing multiphase currents rich in harmonics, from which multiphase current of high frequency may be produced, or high frequency multiphase current from another source 5 may be compared with single phase standards for checking frequencies with great accuracy. The circuits of my invention include an arrangement of condenser which discharges through a resistance or an inductance which discharges 10 through a resistance in the establishment of oscillations by the relaxation method.

Referring to the drawings in detail, Fig. 1 illustrates triode tubes 1, 2 and 3 having the plate electrodes 1c, 2c and 3c thereof connected in delta 15 through inductance elements 7, 8 and 9. The output circuit of one tube is impedance coupled to the input circuit of the adjacent tube. The single phase high frequency energy obtained from any suitable source such as represented at 4 is 20 supplied to the input winding of the transformer 5. The output of transformer 5 is tuned by means of the variable condenser 6. The tuned circuit leading from condenser 6 connects to the control grid 1a of triode tube 1 and to the input 25 circuit of the triode tube through impedance 10.

The output circuit of triode tube 1 includes the inductance 7 and the source of potential 11. Bypass condenser 11a is connected across the source of potential 11. Condenser 12 connects between 30 the input circuit of triode tube 1 and the output circuit of triode tube 3. Triode tube 2 has the output circuit thereof completed from anode 2c through inductance 8 having a source of potential 13 in circuit therewith. Condenser 13a 35 serves as a high frequency bypass condenser around the source 13. The input circuit of tube 2 includes impedance 14. A condenser 15 connects between the input circuit of triode tube 2 and the output circuit of tube 1. Triode tube 3 has 40 its output circuit completed from anode 3c through inductance 9 and source of potential 16. Condenser 16a serves as a bypass for high frequency currents around source 16. The input 45 circuit of triode tube 3 includes impedance 17 connected between the input and output circuits of triode tube 3 as shown. Condenser 18 connects between the input circuit of triode tube 3 and the output circuit of triode tube 2. The delta arrangement of the anodes 1c, 2c and 3c 50 and the impedance coupling between the output circuit of one tube and the input circuit of the adjacent tube with the control applied to the control grids 1a, 2a and 2b, enables the circuit to establish three phase oscillations which are 55 controlled by the single phase oscillations impressed from the source upon the input circuit of the tubes for effecting a division in frequency and producing a sub-harmonic frequency delivered to the output circuit designated at 20.

60 In Fig. 2 I have shown a circuit arrangement in which the control grids 1a, 2a and 3a of the triodes 1, 2 and 3 are connected in delta with the input and output circuits of adjacent tubes intercoupled through impedance couplings, the control current being impressed upon one of the control grids for effecting the frequency division. The source of potential is impressed upon the input circuit of triode tube 1 directly across impedance 19 which connects to the input circuit of tube 1. Capacity coupling is provided as indicated at 19 between the potential source 4 and the input circuit of triode tube 1. The arrangement of the elements in the input and output circuits of the tubes is similar to the corresponding 65 numbered parts illustrated in Fig. 1. The en-

ergy of divided frequency is delivered from the output circuit 20.

In Fig. 3 I have shown the triodes arranged in a circuit with anodes 1c, 2c and 3c connected in Y. The grid electrodes 1a, 2a and 3a are likewise connected in Y with the output and input circuits of adjacent tubes coupled through an impedance coupling. The arrangement of the elements is similar to the arrangement illustrated in Figs. 1 and 2 except that in the Y connected system a single source of anode potential 21 is provided with inherent simplification. The source of input high frequency energy is shown at 4 capacity coupled through condensers 19 and resistance 60 to the control grids 1a, 2a and 3a through the common bus 22 and through resistors 23, 24 and 25 as shown. The anodes are connected through impedances 7, 8 and 9 to common bus 26 which connects to the source of potential 21. Condenser 33 is provided in shunt with potential source 21. Condensers 15, 18 and 12 intercouple the input and output circuits of adjacent triodes. The high frequency energy supplied at 14 is subjected to a division in frequency delivered at terminals 20.

It will be observed that I have shown inductance elements at 7, 8 and 9, in the circuits of the triodes in Figs. 1, 2 and 3. I may employ resistance elements arranged in combination similar to the inductance elements of Figs. 1, 2 and 3 as will be understood more fully from a consideration of Figs. 4, 5 and 6.

In Fig. 4 I have shown the triodes 1, 2 and 3 having their anodes connected in delta and the input and output circuits coupled through resistance elements arranged for the operation of the system as a frequency divider. The output circuit of triode 1 includes resistance element 27. The output circuit of triode 2 includes resistance element 28. The output circuit of triode 3 includes resistance element 29. The other elements in the circuit correspond to similarly numbered elements illustrated in Figs. 1, 2 and 3. I provide bypass condensers in shunt with the sources of potential as represented at 11a, 13a and 16a. I arrange condensers 33, 34 and 35 in shunt with resistance elements 10, 14 and 17 in the input circuits of triodes 1, 2 and 3, respectively. I have shown the input potential from source 4 supplied through transformer 5 and tuning condenser 6 through the input circuit of triode 3. The input potential may be supplied directly at the input circuit of any one of the tubes in the polyphase circuit. The polyphase energy of divided frequency is delivered at output terminals 20.

In Fig. 5 I have illustrated a form of my invention where the grid electrodes 1a, 2a and 3a are connected in delta. The input and output circuits of adjacent tubes are intercoupled to resistors 27, 28 and 29. The control current is applied from the single phase source 4 which connects to the input circuit across grid 1a and cathode 1b of electron tube 1, which input circuit is shunted by resistance 18. The remaining elements are arranged in a manner similar to the elements illustrated in Fig. 2 wherein the relaxation circuit condensers 12, 15 and 18 connect between the anode and control grids of the tubes in the manner shown. The sub-harmonic polyphase current is obtained in the output circuit represented at 20.

Fig. 6 illustrates a circuit embodying my invention in which the plate electrodes of the tubes 75 1, 2 and 3 are connected in Y and the grid elec-

trodes also connected in Y with the input and output circuits of the adjacent tubes connected through resistances. The input circuit from source 4 is connected through condensers 19 with resistance 60 which connects at one side to each of the control grid electrodes 1a, 2a and 3a through the common bus 22 and through resistors 23, 24 and 25 as described in connection with Fig. 3. The plate electrodes are connected in Y through resistors 27, 28 and 29 which are connected through the common bus 26 with the source of anode potential illustrated at 21. The relaxation circuit charging condensers are represented at 12, 15 and 18. The polyphase sub-harmonic current is delivered at the output circuit shown at 20.

Fig. 7 shows another arrangement of the circuit of my invention in which the electron tubes 1, 2 and 3 have their circuits connected in delta with the input and output circuits of adjacent tubes inductively coupled. The circuits are arranged to receive high frequency energy from the source and deliver a sub-harmonic polyphase current at the output circuit 20. The source 4 is connected through coupling condensers 19 across the grids of adjacent tubes. It will be understood that in this as in all forms of my invention, the source may be connected in any of the various ways shown in the drawings, such as between the control grid 3a of tube 3 and the opposite side of the input circuit of the tube 3 through inductance 37 by means of coupling condensers or a coupling transformer. The input circuit of tube 1 includes inductance 38. The input circuit of tube 2 includes inductance 39. The output circuit of tube 1 includes inductance 7 which is inductively related to inductance 37. The output circuit of tube 2 includes inductance 8 which is inductively coupled with inductance 38. The output circuit of electron tube 3 contains inductance 9 which is inductively related to inductance 39 as shown. The sub-harmonic polyphase currents are delivered at circuit 20.

Fig. 8 shows a modified arrangement of my invention wherein the triodes have their plate circuits arranged in delta and the input and output circuits of adjacent tubes inductively coupled for establishing the oscillatory system which receives the high frequency energy and derives the sub-harmonic energy of polyphase characteristic. In this arrangement the inductances 7, 8 and 9 are arranged in delta while inductances 37, 38 and 39 are each disposed in the input circuits of successive tubes and inductively coupled with the delta connected anode circuit windings. In this arrangement the source 4 is connected through condensers 19 with the grid electrode 1a of electron tube 1 and the cathode 1b of electron tube 1, thereby impressing the single phase high frequency oscillations across the input of tube 1 while polyphase oscillations of divided frequency are derived from the output circuit 20. In each instance the inductances 7, 8 and 9 fix the time constant of the plate circuits of the tubes.

Fig. 9 shows a further modified form of the circuit of my invention wherein the plate electrodes of tubes 1, 2 and 3 are connected in Y and the grid electrodes are connected in Y with the input and output circuits of adjacent tubes inductively coupled through transformer systems and the circuits arranged for the impression of high frequency energy on the control grids from the source 4 for deriving polyphase sub-harmonic energy in the output circuit of the several tubes from output circuit 20. In this arrangement

the source 4 is connected through condensers 19 with resistance 60 which connects at one end to the common bus 22 which is electrically connected through inductance elements 37, 38 and 39 with the grid electrodes 1a, 2a and 3a, respectively. The output circuits each include inductance elements 7, 8 and 9 connected to bus 26 and disposed in Y and respectively coupled with inductances 37, 38 and 39. The source of potential 21 connected to bus 26 and to the common cathode connection, indicated at 70, provides means for energizing the plate circuits of all of the electron tubes. The condenser 36 connects in shunt with the source of potential 21 as shown. The high frequency energy impressed from source of potential 4 upon the circuits of the electron tubes is divided and a polyphase sub-harmonic current produced in the output circuit 20. It will be observed that in all of the arrangements described in Figs. 1-9, the triodes are operated by control current applied to the control grids of the several tubes. I may provide arrangements where tetrodes are employed in the frequency division system of the control current applied to the screen grids as illustrated for example in Figs. 10-18.

Referring particularly to Fig. 10 I have shown tetrodes 40, 42 and 43 each including a control grid as represented for example at 40a, a cathode as represented at 40b, an anode as represented at 40c, and a screen grid element as represented at 40d. The screen grids are connected in Y. The plate electrodes are connected in Y. The control current from the source 4 is impressed across the screen grid circuits. The output circuit of one electron tube is inductively coupled to the input circuit of a succeeding electron tube in the oscillator system. That is to say the transformer 44 has its primary winding 44a connected in the output circuit of electron tube 41 and its secondary winding 44b connected in the input circuit of electron tube 43. Electron tube 43 has its output circuit coupled through transformer 45 with the input circuit of electron tube 42. Transformer 45 has its primary winding 45a connected in the output circuit of electron tube 43 and its secondary winding 45b connected in the input circuit of electron tube 42. The output circuit of electron tube 42 is coupled through transformer 46 with the input circuit of electron tube 40, that is primary winding 46a is disposed in the output circuit of electron tube 42 and secondary winding 46b is connected in the input circuit of electron tube 40. The screen grid elements 40d, 43d and 42d are connected to resistance elements 47, 48 and 49 with the common bus 50 which connects to one side of the input source 4. The opposite side of the input source 4 connects through the lead which extends to the point 51 which connects in common to each of the cathodes 40b, 43b and 42b. The portion 52 of the battery 53 is utilized for applying a predetermined potential on each of the screen grids. The battery 53 is included in the plate circuits of all of the electron tubes. The polyphase energy of reduced frequency is supplied to the output circuit shown at 20.

Fig. 11 illustrates a delta connected system for a set of tetrodes where the input and output circuits of the tubes are transformer connected one to the other with the control current applied to the screen grid circuit. The elements used in the delta connected circuit of Fig. 11 which are common to the Y connected circuit of Fig. 10 have been indicated by similar reference char- 75

acters. The impressed energy in source 4 is applied to the input circuit of the transformer 5 and impressed upon the screen grid electrode 42d of tetrode 42. The transformers 44, 45 and 46 have their secondary windings 44b, 45b and 46b connected in delta and connected to the control grid electrodes 40a, 42a and 43a of each of the tetrodes as shown. The output circuit of each tetrode extends from the anode of each tetrode 10 through its associated primary winding as represented at 44a, 45a and 46a. In this arrangement each output circuit is supplied with an independent source of potential as shown at 54, 55 and 56. On each of these sources I provide taps 54a for 15 applying predetermined potential to the screen grid electrode 43d, a tap 55a for supplying predetermined potential to the screen grid electrode 42d and a tap 56a for applying predetermined potential to the screen grid electrode 40d. The 20 output polyphase energy of reduced frequency is delivered by circuit 26.

Fig. 12 shows a further circuit arrangement embodying my invention wherein the screen grid tubes have their plate electrodes connected in delta and the input and output circuits of the tubes inductively coupled. I have employed reference characters similar to those shown in Figs. 10 and 11 to designate similar elements in Fig. 12. It will be observed that the plate electrodes 40c, 43c and 42c are connected in delta arrangement. The transformers 44, 45 and 46 have their windings arranged for inductively coupling the input and output circuits of the several tubes. The control current is supplied 30 from the source 4 through transformers 57, 58 and 59 as shown. The secondary windings of each of the transformers 57, 58 and 59 connect with the screen grid electrodes of each of the electron tubes as shown. A separate potential 35 source is provided for each of the tubes 40, 42 and 43 by which the cathodes are heated, the required potential applied to the screen grids and the required potential supplied to the anodes. The polyphase energy of reduced frequency with 40 respect to the impressed frequency of the source 4 is delivered by output circuit 29.

Fig. 13 illustrates a further modified form of my invention employing screen grid tubes with the plate electrodes arranged in delta and having the control current supplied to the screen grid elements of the tubes, but have an impedance coupling between the input and output circuits of the tubes. The input from source 4 passes through coupling condensers 19 and impedance 45 60 by which the control current is impressed upon screen grid electrode 40d. The input of each tube is completed through impedance 10, 17 and 14 as illustrated. The impedance elements which are disposed in the delta connected circuit are 50 similar to those employed in the arrangement of Figs. 1 and 2, and have been represented at 7, 8 and 9. Each electron tube is provided with an independent potential source as represented at 11, 13 and 16. The screen grid of each tube 55 connects to a point on the respective sources of potential as shown at 11b, 13b and 16b. The potential to each of the screen grids is supplied 60 through impedance elements which I have represented at 60, 61 and 62. The charging condensers employed in association with each of the relaxation oscillator circuits are represented at 65 70 12, 18 and 15. The energy of divided frequency is delivered at the output terminals 20.

As represented in Fig. 14 the tetrodes may be 75 arranged with the plate circuits connected in

Y, the screen grid circuits connected in Y and the control grid circuits connected in Y. In this arrangement the screen grids 40d, 42d and 43d are all shunted to the common bus 63. The control grid electrodes are connected in a manner similar to the connection of the control grid electrodes in Figs. 3 and 6. That is, the control grids are bonded to a common bus 22 through charging resistors 23, 24 and 25. The output circuits are connected to a common bus 26 through inductances 7, 8 and 9 in a manner similar to the arrangement described in Figs. 3 and 6. A common source of potential 53 is employed for energizing the screen grid and anode circuits of the several tubes. The section 52 of the source 53 is employed for energizing the screen grid electrodes. The charging condensers are shown at 12, 15 and 18. The polyphase energy of reduced frequency is delivered from output circuit 20 as illustrated.

In Fig. 15 I have shown a circuit arrangement where a grid electrode of the tetrodes are connected in delta and the input and output circuits of adjacent tubes coupled through impedances, the control current being supplied to the screen grid of one of the tetrodes at single phase and being modified to obtain a polyphase current of reduced frequency at the output terminals of the apparatus. The input current is impressed upon screen grids 40d, 43d and 42d. The impedance elements 7, 8 and 9 are arranged in a manner similar to the impedance elements in Fig. 2. The input circuit of each tube is closed through impedance 10, 14 and 11. Proper bias potentials on the screen grids are obtained from sources 11, 13 and 16 through taps 11b, 13b and 16b. The charging resistances are shown for tubes 42 and 43 at 62 and 61 respectively. The charging condensers are shown at 12, 15 and 18.

Fig. 16 shows a modified form of the circuit of my invention wherein the screen grid tubes 40, 42 and 43 have their plate circuits connected in delta and the circuits of one tube coupled to the circuits of an adjacent tube through a resistance coupling where the control current is applied to the screen grid electrodes. The screen grid electrodes are designated at 40d, 42d and 43d, one of them, namely 40d, being energized from source 4 connected across resistance 60. The resistance elements 21, 28 and 29 are arranged in a manner similar to the arrangement described in connection with Fig. 4 for providing a delta circuit with respect to the plate electrodes of each of the tubes. The charging condensers for the relaxation circuit oscillator system are shown at 12, 15 and 18. The polyphase current of reduced frequency is delivered at output terminals 20.

In Fig. 17 I have shown a circuit arrangement for tetrodes wherein the grid circuits are connected in delta and the adjacent tubes interconnected through resistance elements, the control potential being supplied to the screen grid electrodes. In this arrangement the control grids 40a, 43a and 42a are connected in delta as shown. The potential supplied from source 4 through coupling condensers 19 and resistance 60 is impressed upon the screen grid 40d, in the manner shown. In order to provide for the proper potential on each of the screen grid electrodes I have shown auxiliary potential sources at 64, 70, 65 and 66. Coupling resistors have been shown at 21, 28 and 29. The polyphase energy of reduced frequency is delivered at the output terminals 20.

In Fig. 18 I have illustrated a system of tetrodes 75

where the screen grids are connected in Y, the plate electrodes connected in Y and the control grids connected in Y but having the adjacent circuits of the tubes connected through resistance elements and the control potential applied to the screen grids of each of the tubes. In this arrangement I have shown the source 4 connected through coupling condensers 19 to the selector circuit 67 and to the screen grid circuit of the several tubes through the common bus 63. The portion 52 of battery 53 is employed for biasing screen grid electrodes. The plate electrodes are connected in Y through resistance elements 27, 28 and 29 which connect to the common bus 26. The control grid electrodes connect through resistors 23, 24 and 25, constituting the charging resistors in this particular embodiment of the invention, to the common bus 22. The screen grid electrodes 40d, 42d and 43d connect through biasing resistors to the common bus 63 as heretofore explained for establishing a Y connected circuit for the screen grid electrodes. The charging condensers for the relaxation oscillator circuit are indicated at 12, 15 and 18. The subharmonic frequency of polyphase characteristic is delivered to the output circuit represented at 20.

In Figs. 19-27 I have illustrated circuit arrangements for the frequency division system of my invention wherein tetrodes are employed connected in three phase relation with the control current applied to the control grids of the tetrodes as distinguished from the application of the control current to the screen grids as set forth in Figs. 10-18.

In Fig. 19 the tetrodes 40, 42 and 43 have the plate circuits thereof connected in delta and the input and output circuits of the tube inductively coupled. The control current is applied to the control grids 40a, 42a and 43a. The plate circuits are each connected to separate sources of potential represented at 11, 13 and 16. The plate circuits are connected in delta and connected to the output terminals indicated at 20. The input circuit is supplied to each of the control grids through transformers 57, 58 and 59 which have their primary windings connected in series and each of which have secondary windings individual to the control grid circuits of each of the tubes. The screen grid circuits which extend from screen grids 40d, 42d and 43d each include a coupling inductance constituting the primary winding of the coupling transformers. The coupling transformers are shown at 44, 45 and 46. The primary windings are connected in the screen grid circuits and the secondary windings are connected in the delta connected output circuit as shown.

In Fig. 20 I have shown a modified arrangement in which the tetrodes 40, 42 and 43 have their elements connected in Y with impedance coupling means between the several circuits of the tetrodes and with the control current impressed upon the control grid of each of the tetrodes. The input circuit from source 4 connects to potentiometer 60, the opposite ends of which are connected across the cathode and control grids of all of the tubes. The cathodes are connected in Y at the common point 70 as shown. The control grids are connected to resistors 10, 14 and 17 to the other side of the potentiometer 60. The plate electrodes 40c, 42c and 43c are connected in Y into the output circuit 20 for delivering polyphase energy at divided frequencies. The input and output circuits of the tubes are coupled to the impedances 1, 8 and 9. The

screen grids 40d, 42d and 43d are connected in Y through resistors to a point of intermediate potential on the potential source 53 as shown. The charging condensers for the relaxation circuit are shown at 12, 15 and 18.

In Fig. 21 I have shown a circuit similar to the circuit illustrated in Fig. 20 except that resistance elements 27, 28 and 29 are employed for interconnecting the several circuits of the tubes 40, 42 and 43. The control current is supplied to the control grids 40a, 42a and 43a, through resistors 10, 17 and 14. The screen grids 40d, 42d and 43d are connected to the point of intermediate potential on source 53 through resistors 71, 72 and 73. The charging condensers for the relaxation oscillator circuit are shown at 12, 15 and 18.

Fig. 22 shows a circuit arrangement for the frequency guider of my invention where the circuits of the tubes 40, 42 and 43 are impedance coupled. The screen electrodes 40d, 42d and 43d are connected in delta. The control current is supplied from source 4 to the transformers 54, 58 and 57 to the control grids 40a, 42a and 43a. Each of the output circuits includes a coupling inductance 7, 8 and 9 connected in circuit with independent sources of potential 11, 13 and 16. The charging resistances are shown at 71, 72 and 73. The charging condensers are shown at 12, 15 and 18. The polyphase output current is delivered to the terminals 20 at a divided frequency with respect to the frequency of the input current at terminals 4.

In Fig. 23 I have shown a circuit arrangement similar to the circuit arrangement shown in Fig. 22 except that resistance elements are used instead of impedance elements for the several tubes. The resistances illustrated at 27, 28 and 29 serve as coupling means for the tube circuits. The remaining elements described in connection with Fig. 22 are employed in a similar relationship in the circuit of Fig. 23.

In Fig. 24 I have shown a further modified form of my invention wherein the screen grids 40d, 42d and 43d are connected in delta and the circuits of the several tubes inductively coupled by means of transformers 44, 45 and 46 for establishing the oscillatory path through the frequency division system. The control current for the several tubes is applied to transformers 54, 57 and 58 to the control grids of each of the tubes. Independent potential sources are provided for the several plate circuits as represented at 11, 13 and 16. The energy of polyphase characteristic is divided with respect to the frequency of the energy impressed at terminals 4 and is delivered at the output terminals 20.

In Fig. 25 a further modified form of the system of my invention is employed wherein a Y connected circuit for the control grids, a Y connected circuit for the plate electrodes and a Y connected circuit for the screen grids are provided with the control current applied from the source 4 to the control grids. I have shown the control grids 40a, 42a and 43a connected to the upper potential end of potentiometer 10 while the lower end of the potentiometer 10 is connected through biasing source 74 to the common cathode connection 70. The plate and screen grid electrodes have their circuits coupled through transformer 44, 45 and 46, the respective windings being connected in Y. The common potential source 53 is provided with a tap thereon for supplying intermediate potential to the screen grid electrodes 40d, 42d and 43d. The polyphase energy of divided

frequency is delivered to output terminals 20. In Fig. 26 I have shown a circuit arrangement where the plate electrodes are connected in delta with resistance coupling between the input and output circuits of each of the tubes. The resistance coupling has been shown at 21, 28 and 29 connected with the plate circuits of the tubes which are disposed in delta. The charging resistances are connected in the screen grid circuits and are shown at 71, 72 and 73 connected to points of intermediate potential in the plate circuit sources 11, 13 and 16. The charging condensers are shown at 12, 15 and 18. The control grid is introduced through the control grid circuits in each of the transformers 56, 57 and 58. Suitable potential sources are applied to each of the input circuits for biasing the control grids at selected potentials.

Fig. 27 shows a form of my invention in which the input and output circuits of the tubes are coupled through inductance elements 1, 8 and 9 with the plate circuits of the tubes connected in delta and the control current applied to the control grids. The input current from the source 4 leads through transformers 54, 57 and 58 to the control grids 40a, 42a and 43a of the tetrodes. The plate electrodes are connected in delta and include inductance elements 7, 8 and 9 in circuit with the independent sources of potential 11, 13 and 16 as shown. The charging resistances are shown at 71, 72 and 73. The charging condensers are indicated at 12, 15 and 18. The polyphase energy of divided frequency is delivered at output terminals 20.

I have found the several embodiments of my invention practical in assembly and operation. I have successfully effected frequency division of an impressed frequency of twenty-five kilocycles to derive three phase energy at one kilocycle. While I have set forth many of the preferred embodiments of my invention I desire that it be understood that other combinations of elements may be employed and that the circuits illustrated are not to be considered in a limiting sense but as illustrating various forms of my invention. No limitations upon my invention are intended other than are imposed by the scope of the appended claims.

The invention described herein may be manufactured and used by or for the Government of the United States of America for governmental purposes without the payment of any royalties thereon or therefor.

What I claim as new and desire to secure by Letters Patent of the United States is as follows:

1. In a frequency division system, a multiplicity of electron tubes, circuit means interconnecting said tubes in polyphase relationship and having an input and an output circuit, means for impressing single phase current of a predetermined frequency on said input circuit and means included in said circuit means for deriving at said output from said multiplicity of electron tubes connected in polyphase arrangement, a polyphase current having a frequency which is a sub-multiple of the impressed frequency.

2. In a frequency division system, circuit means including an input circuit and an output circuit, a multiplicity of electron tubes interconnected by said circuit means in Y formation, means for impressing single phase current of a predetermined frequency on said input circuit, and means included in said circuit means for deriving from said output circuit a polyphase current having a

frequency which is a sub-multiple of the impressed frequency.

3. In a frequency division system, circuit means including an input circuit and an output circuit, a multiplicity of electron tubes connected by said circuit means in delta formation, means for impressing single phase current of a predetermined frequency on said input circuit, and means included in said circuit means for deriving from said output circuit a polyphase current having a frequency which is a sub-multiple of the impressed frequency.

4. In a frequency division system, circuit means including an input circuit, a multiplicity of electron tubes connected in polyphase formation by said circuit means, each of said tubes including a control electrode connected with a condenser and a resistance, an output circuit included in said circuit means and connected with said electron tubes, means for impressing single phase current of a predetermined frequency on said input circuit, and means for deriving from said multiplicity of electron tubes connected in polyphase arrangement, a polyphase current having a frequency which is a sub-multiple of the impressed frequency.

5. In a frequency division system, circuit means including an input circuit, a multiplicity of electron tubes connected in polyphase formation by said circuit means, an output circuit included in said circuit means and connected with said electron tubes, impedance elements for coupling the input electrode of one tube and output electrode of another tube in a reentrant cascade formation, means for impressing single phase current of a predetermined frequency on said input circuit and an output circuit included in said circuit means and connected with said multiplicity of electron tubes for delivering polyphase current having a frequency which is a sub-multiple of the impressed frequency.

6. In a frequency division system, circuit means including an input circuit, a multiplicity of electron tubes connected by said circuit means in polyphase formation, an output circuit included in said circuit means and connected with said electron tubes, means for coupling the input and output electrodes of each of said electron tubes, and means included in said circuit means for impressing single phase current of a predetermined frequency on said input circuit for delivering at said output circuit polyphase current having a frequency which is a sub-multiple of the impressed frequency.

7. In a frequency division system, circuit means, a multiplicity of electron tubes connected by said circuit means in polyphase arrangement, an input circuit included in said circuit means and connected with the control grids of said electron tubes, an output circuit included in said circuit means and connected with said electron tubes, said circuit means coupling the input and output circuits of each of said electron tubes to form a reentrant cascade, means for impressing single phase current of a predetermined frequency on the control grids of said electron tubes, and means for delivering polyphase current to said output circuit at a frequency which is a sub-multiple of the impressed frequency.

8. In a frequency division system, a multiplicity of tetrode electron tubes each including a control grid, a screen grid, a cathode and an anode, circuit means interconnecting said tetrode electron tubes in polyphase arrangement, an input circuit connected with the control grids of

- 5 said tetrode electron tubes, an output circuit connected with said tetrode electron tubes, means coupling the input and output circuits of each of said tetrode electron tubes in reentrant cascade, 5 means for impressing single phase current of a predetermined frequency on the control grid circuits of said tetrode electron tubes, and means for deriving polyphase current in said output circuit having a frequency which is a sub-multiple of the impressed frequency.
- 10 9. In a frequency division system, a multiplicity of tetrode electron tubes each including a control grid, a screen grid, a cathode and an anode, means interconnecting the electrodes of 10 said tetrode electron tubes in polyphase arrangement, an input circuit connected with one of the electrodes of each said tetrode electron tubes, an output circuit common to all of said tetrode electron tubes, means for impressing single phase current of a predetermined frequency on the screen 15 grids of said tetrode electron tubes, and means for deriving a polyphase current having a frequency which is a sub-multiple of the impressed frequency in the output circuit of said tetrode 20 electron tubes.
- 15 10. In a frequency division system, a multiplicity of tetrode electron tubes each having a screen grid, a control grid, a cathode and an anode, circuit means intercoupling the input and output 25 circuits of each of said tetrode electron tubes in delta formation, an input circuit included in said circuit means connected with said control grids for impressing single phase current on said circuits, an output circuit included in said circuit means common to said tetrode electron tubes, and means for deriving in said output circuit a polyphase current having a frequency which is a sub-multiple of the impressed frequency.
- 20 11. In a frequency division system, a multiplicity of tetrode electron tubes each having a screen grid, a control grid, a cathode and an anode, circuit means intercoupling the input and output electrodes of each of said tetrode electron tubes, circuits interconnecting said tetrode 25 electron tubes in Y formation an input circuit included in said circuit means and connected with said control grids for impressing single phase current on said circuit means, an output circuit included in said circuit means and common to said tetrode electron tubes, and means for deriving in said output circuit a polyphase current having a frequency which is a sub-multiple of the impressed frequency.
- 25 12. In a frequency division system, circuit means a multiplicity of tetrode electron tubes each having a screen grid, a control grid, a cathode and an anode, impedance elements included in said circuit means and interconnecting the input and output circuits of each of said tetrode 30 electron tubes, said circuit means interconnecting said tetrode electron tubes in delta, an input circuit included in said circuit means and connected

5 with one of the grids of each said tetrode electron tubes for impressing single phase current upon said circuits, an output circuit included in said circuit means and common to all of said tetrode electron tubes, and means for deriving in said output circuit a polyphase current which is a sub-multiple of the impressed frequency.

10 13. In a frequency division system, circuit means, a multiplicity of tetrode electron tubes each having a screen grid, a control grid, a cathode and an anode, means included in said circuit means intercoupling the input and output circuits of each of said tetrode electron tubes, circuit means interconnecting the electrodes of said tetrode electron tubes in Y formation, an input circuit included in said circuit means and connected with the control grids of said tetrode electron tubes for impressing single phase current on said circuits, an output circuit included in said circuit means and common to said tetrode electron tubes, and means for deriving in said output circuit a polyphase current having a frequency which is a sub-multiple of the impressed frequency.

15 14. In a frequency division system, circuit means, a multiplicity of tetrode electron tubes each having a screen grid, a control grid, a cathode and an anode, circuits included in said circuit means for intercoupling the input and output circuits of each of said tetrode electron tubes, said circuit means interconnecting said anodes in Y, said control grids in Y, and said screen grids in Y, means included in said circuit means and interconnecting said control grids and said anodes, an input circuit for impressing single phase current on said control grid electrodes, an output circuit common to said tetrode electron tubes, and means for deriving in said output circuit a polyphase current having a frequency divided with respect to the impressed frequency.

20 15. In a frequency division system, circuit means, a multiplicity of tetrode electron tubes each having a screen grid, a control grid, a cathode and an anode, said circuit means intercoupling the input and output circuits of each of said tetrode electron tubes and interconnecting said tetrode electron tubes in delta, a charging circuit comprising a condenser and an impedance included in said circuit means and connected with each of said tetrode electron tubes for establishing a relaxation circuit oscillatory path for the production of polyphase currents, an input circuit included in said circuit means and connected with one of the grids of said tetrode electron tubes for impressing single phase current on said circuits, and an output circuit included in said electron tubes and common to said tetrode electron tubes for delivering a polyphase current having a frequency divided with respect to the impressed frequency.
